UNITED STATES PATENT OFFICE.

ANDREW C. VAUCLAIN, OF PHILADELPHIA, PENNSYLVANIA.

DRILLING-TOOL.

984,323.

Specification of Letters Patent. Patented Feb. 14, 1911.

Application filed June 13, 1910. Serial No. 566,684.

To all whom it may concern:

Be it known that I, ANDREW C. VAUCLAIN, a citizen of the United States, residing in Philadelphia, Pennsylvania, have invented 5 certain Improvements in Drilling-Tools, of which the following is a specification.

My invention relates to boring tools, twist drills and the like, and the object of my invention is to provide a tool of this character 10 with a maximum amount of cutting edge whereby the effective cut of the same may be increased and facilitated and undue heating of the drill, particularly at the central portion of or adjacent to the cutting edge 15 may be avoided.

My invention is particularly applicable to drills familiarly known as "high speed drills", and in the drawings herewith I have shown several tools within the scope of my 20 invention, in which:

Figure 1, is a view of the cutting end of one form of drill embodying my invention; Fig. 2, is a side elevation of the same; Fig. 3, is an edge view of the cutting end; Fig. 25 4, is a perspective view of the cutting end, and Fig. 5, is a view similar to Fig. 1, showing a slightly modified construction.

In the manufacture of ordinary twist or flat drills, the cutting end is of such a character that a substantially straight portion is left at the end intermediate the beveled angular cutting edges, and the work of such straight portion is in the nature of a grinding or twisting of the metal against which 30 it is directed, with the result of undue heating, and in many instances, the burning off of such portion with the consequent necessity of cutting away a portion of the tool before it may be sharpened for further use, 35 and the possible retempering of such tool. It has been proposed to point drills of this type, but in all instances of which I am aware the pointing has been effected in such manner as to leave relatively little metal to 40 serve as a support for such point, and in consequence the torsional strain applied to the tool has caused such point to break off. In the construction that I have adopted, I bring the cutting edges of the tool, of which 45 there will be a plurality in all instances to a common center or point at which there is consequently no motion and hence relatively little or no heating produced. To effect this

result, I provide a bar of a peculiar section, comprising side or web portions 1 and 2, 55 lapping at the center as indicated at 3, so that the plane of one portion on one side of the tool is directly in line with the plane of the other portion on the other side of the tool. The end of each portion 1 and 2 of 60 such structure is then ground to the proper bevel, as indicated at 4, bringing the cutting edges to a central line α , and then by reducing the material of each section adjacent a line at an angle, preferably at a right angle 65 to the plane of the cutting edges as indicated at γ , the cutting edges are brought to an actual central point with sufficient metal behind them to support the structure in its work. In Fig. 1, the construction is wholly 70 angular and is probably sufficient for all purposes, but in cases where additional strength is needed or required I may provide the section with fillets 5 at the points where the portions 1 and 2 join the central 75 web 3, as indicated in Fig. 5.

The tool made in accordance with my invention having greater cutting area may be driven with much less power and accomplish more work in a given length of time. At 80 the same time, there will be no undue heating such as is occasioned in the use of drilling tools of the ordinary character.

As may be understood, my invention is applicable to all forms of flat or twist drills 85 or tools designed for drilling purposes, and my claims are to be construed as covering such structures.

I claim:

1. A drill having a pair of integrally connected webs with a lapping central portion, each web having a cutting edge formed by beveling the end of the same, the lapping portion of each web being removed adjacent the cutting edges whereby they are brought 90 to a common center or point.

2. A drill having a pair of integrally connected webs in different planes with a lapping central portion, each web having a cutting edge formed by beveling the end of the 100 same, said cutting edges lying in the same plane, and the lapping portion of each web being removed adjacent said cutting edges whereby they are brought to a common center or point.

3. A drill having a plurality of integrally

connected webs in different planes with a lapping central portion, each web having a cutting edge formed by beveling the end of the same, and said cutting edges meeting at 5 a central point by reducing the lapping portions of each web at an angle with respect to said cutting edges.

In testimony whereof, I have signed my name to this specification, in the presence of two subscribing witnesses.

ANDREW C. VAUCLAIN.
